(57) **CLAIM**

The ornamental design for a conveyor, as shown and described.

DESCRIPTION

FIG. 1 is a rear perspective view of a conveyor showing my new design;

FIG. 2 is a front view thereof;

FIG. 3 is a rear view thereof;

FIG. 4 is a right side view thereof;

FIG. 5 is a left side view thereof;

FIG. 6 is an enlarged bottom view thereof; and,

FIG. 7 is an enlarged top view thereof;

FIG. 8 is a front perspective view thereof;

FIG. 9 is a partial enlarged view showing the area "9" in FIG. 1; and,

FIG. 10 is a partial enlarged view showing the area "10" in FIG. 8.

The dot-dash broken lines indicating an enlargement portion of the design form no part of the claimed design.
